(57) CLAIM

I claim the ornamental design for an earbud, as shown and described.

DESCRIPTION

FIG. 1 is a top perspective view of a first embodiment of an earbud showing the new design;

FIG. 2 is a bottom perspective view of the earbud of FIG. 1.

FIG. 3 is a left-side view of the earbud of FIG. 1.

FIG. 4 is a right-side view of the earbud of FIG. 1.

FIG. 5 is a rear view of the earbud of FIG. 1.

FIG. 6 is a front view of the earbud of FIG. 1.

FIG. 7 is a top view of the earbud of FIG. 1.

FIG. 8 is a bottom view of the earbud of FIG. 1.

FIG. 9 is a top perspective view of a second embodiment of an earbud showing the new design;

FIG. 10 is a bottom perspective view of the earbud of FIG. 9.

FIG. 11 is a left-side view of the earbud of FIG. 9.

FIG. 12 is a right-side view of the earbud of FIG. 9.

FIG. 13 is a rear view of the earbud of FIG. 9.

FIG. 14 is a front view of the earbud of FIG. 9.

FIG. 15 is a top view of the earbud of FIG. 9.

FIG. 16 is a bottom view of the earbud of FIG. 9.

FIG. 17 is a top perspective view of a third embodiment of an earbud showing the new design;

FIG. 18 is a bottom perspective view of the earbud of FIG. 17.

FIG. 19 is a left-side view of the earbud of FIG. 17.

FIG. 20 is a right-side view of the earbud of FIG. 17.

FIG. 21 is a rear view of the earbud of FIG. 17.

FIG. 22 is a front view of the earbud of FIG. 17.

FIG. 23 is a top view of the earbud of FIG. 17; and,

FIG. 24 is a bottom view of the earbud of FIG. 17.

The dash-dash broken lines represent portions of the earbud that form no part of the claimed design. The dash-dot broken lines represent a boundary of the claimed design and form no part of the claimed design.

The cord is drawn broken away for ease of illustration.
